ROTARY DRIER

Original Filed April 30, 1928

UNITED STATES PATENT OFFICE

1,987,242

ROTARY DRIER

Martin Madsen, Monterey Park, Calif.

Original application April 30, 1928, Serial No. 273,876. Divided and this application October 21, 1930, Serial No. 490,195

6 Claims. (Cl. 34—6)

This application is a division of my copending application entitled Portable asphalt mixing plant, Serial No. 273,876, filed April 30, 1928, and which, issued on December 15, 1931 into Patent No. 1,836,261. The invention which forms the subject-matter of this divisional application is a rotary drier and is intended to dry, or otherwise heat-treat, broken or granular material which may be passed therethrough. The rotary drier of the invention may, if desired, be equipped with a novel screen arrangement which constitutes a part of my invention, and may then be used for drying and also for grading the materials.

15 The object of the present invention is to provide an efficient apparatus of this character which is of simple construction and which is of compact arrangement, which renders it suitable for portable use.

20 Other objects which are inherent in the invention and which reside in the details of construction thereof will be made evident in the detailed description of my invention.

25 My invention in its broad concept includes a drum or treating chamber through which the material to be treated is fed. This drum or treating chamber is preferably rotatable and arranged to be rotated. Extending into one end of the drum is a fire-box or fire-tube which provides 30 this end of the drum with a passage, which passage is formed between the wall of the drum and the fire-box. There is a means for supplying hot gases of products of combustion to the fire-box, which products of combustion or hot gases thereafter pass through the drum. The important advantage accruing from this broad concept of my invention is that the material to be heat-treated is caused to pass through a relatively hot area immediately before it passes from the drum, and is 35 therefore efficiently heat-treated. By locating the fire-box so that it projects into one end of the drum, the heat radiated by the fire-box as well as the heat which is carried by convection through the drum is used for heat-treating the 40 material.

45 In the preferred form of device which includes the broad features of my invention just mentioned, the fire-box as well as the drum is of cylindrical cross-section, and the fire-box is of less 50 diameter than the drum in order that the passage formed by the fire-box may be an annular passage. This is advisable in order that the feeding of the material from the drum may be continuous as the drum is rotated.

55 The fire-box may be stationary and the drum may rotate independently thereof, or the fire-box may be secured to the drum and be rotatable therewith. Although it is not essential to the invention in its broad aspect, I prefer to have 60 the fire-box rotatable with the drum in order that

the fire-box may be used to support a bearing which constitutes a part of the means for rotatably supporting the drum. By this arrangement it is possible to place the support means for the drum on the outside of the apparatus, which is a much simpler construction than would be required if the support means were required to be placed on the inside thereof.

Another feature of the invention which may be optionally incorporated with the broad concept previously mentioned is the provision of a housing around the drum. This housing is provided for reasons of heat economy. The outer end of the fire-box projects to the exterior of the housing and the means for rotatably supporting the drum cooperates with this extending end of the fire-box. By this construction the support means may be located at the exterior of the apparatus where it may be conveniently reached and where it is not subjected to the high heat which exists within the housing.

If the structure pointed out in the above paragraph is used on a material which is to be graded, the apparatus may have incorporated therewith a screening means. My invention provides a 25 screening means which is of annular construction and of larger diameter than the drum so that it may be disposed around the drum. The screening means is partly supported by the fire-box and has a closed end, the closed end being secured to 30 the fire-box. By this arrangement just described it is possible to place the screening means around the end of the drier, as previously mentioned, which is a compact arrangement and which maintains the material passing through the apparatus quite near to the source of heat. If desired, the material may be deposited in bins included 35 within the housing, and this material will be kept warm for a long period of time due to the fact that it is not conveyed to separate storage bins 40 and contacted with the atmosphere.

If desired, the screen arrangement of my invention may be used independent of the fire box arrangement. When such screen arrangement is used independent of the other features of my invention, the screening means is placed around the outlet end of the rotary drum, and a means is extended inwardly beyond the end of the drum so that material passing through the outlet of 45 the drum is guided into the screening means. 50

In the accompanying drawing I have illustrated an apparatus which embodies not only the broad concept of my invention, but also the various additional features which have just been pointed out. It should be understood in illustrating a 55 device including all of the various features of my invention and features of construction, that I do not intend to be limited to the complete combination but intend my invention to be considered as including the essential and fundamental fea- 60

tures by themselves as well as in combination with the other features mentioned which may be optionally employed.

Referring to the drawing in detail,—

5 Fig. 1 is a longitudinal section.

Figs. 2 and 3 are cross-sections taken on the corresponding lines of Fig. 1.

Fig. 4 is a fragmentary cross-sectional view taken on the line 4—4 of Fig. 1.

10 Referring to the drawing in detail, I will describe the embodiment of my invention disclosed thereby. The numeral 11 represents an inclined drier tube or drum through which the material to be heat-treated is passed. The inlet for the 15 drum is provided by an opening 12 within an inverted flange 14 secured to the right end of the drum 11. The means for supplying the material to the drum is provided in the form of a chute 15. Spiral or helical blades 16 are provided near the 20 inlet end of the drum 11 for carrying the material to be treated in a forward direction, and longitudinal agitating members 17 are secured to the interior of the drum near the central part thereof.

Extended into the left end of the drum 11 is a 25 heater tube or fire-box 20 which is of cylindrical cross-section and is smaller in diameter than the drum 11 in order to provide an annular outlet passage 21. The fire-box 20 consists of a metal shell 23 and a lining 24 of refractory material. 30 The fire-box 20 is preferably rigidly secured to the drum by suitable spider members 24a shown best in Figs. 1 and 2. One part of the fire-box 20 projects from the end of the drum 11, as shown.

Surrounding this outlet portion of the drum 11 35 is a screening means designated in general by the numeral 27. The screening means includes inner screens 28 and an outer screen 29. The screens 28 and 29 are frusto-conical in shape, being smaller at their left ends. Secured to the 40 fire-box 20 a distance from the end of the drum 11 is an end plate or annular disc 30 which extends radially outward and has the left ends of one of the screens 28 and the screen 29 secured thereto by suitable attaching angles 32. The end 45 plate 30 serves as a support for the left ends of the screens and also serves as a closure means to prevent material passing from the annular outlet 21 from escaping without being subjected to a screening action. The right end of the screen 50 29 and the adjacent ends of the two screens 28 are supported in a concentric position around the drum 11 by means of a tube or compound spider construction 33 which is secured to these ends of the screens and also to the drum 11. The right 55 end of the right screen 28 is supported in concentric position around the drum 11 by means of a supporting spider 34 secured to this screen and also to the drum. The screens are made frusto-conical in order that the lowermost portions thereof incline slightly to the left and decline slightly to the right in order that there will be a slight gravitational feed of the material which will carry it along the screen and be properly subjected to a screening action.

60 Surrounding the drum 11 is a housing 38 which has a cylindrical portion 39 which surrounds the right end of the drum 11, and has a stack 40 through which the hot gases are taken from the right or inlet end of the drum and from the right 70 end of the housing. The left end of the housing 38 is enlarged, as shown, to accommodate the screening means and also to provide a series of compartments or bins 43, 44, 45, and 46. Cooperating with the outer walls of the housing are 75 partitions 47, 48, and 49 which divide the interior

space into bins 43 to 46 inclusive. The extreme left end of the fire-box 20 extends through an annular opening 50 into an end wall 51 of the housing 38, the opening 50 being but slightly larger in diameter than the external diameter of the fire-box 20 in order that there will be but a minimum of heat lost at this point. Supported in axial alignment with the fire-box and adjacent the end thereof is a burner 52 which is supplied with fuel through a pipe 53. The burner 52 provides a jet of combustible gas 54 which is ignited and produces a flame in the fire-box 20. To prevent a harmful interference with the jet 54 there is provided a flame shield 54a which is located between the burner and the end of the fire-box and which is concentric to the axis thereof. The parts just mentioned constitute the means for delivering the products of combustion or hot gases to the fire-box.

The drum 11 is rotatably supported at its right end by means of a bearing 55 supported on suitable framework 56. Extended through the bearing 55 is a shaft 57, the inner end of which supports a spider 58 to which the right end of the drum is secured. The outer end of the shaft 57 is provided with a gear 59 by means of which it is rotated. The left end of the drum is supported by means of a bearing ring 61 which is concentrically secured on the end of the fire-box which projects outward through the opening 50 of the housing 38. A pair of rollers 62, one of which is arranged on each side of a vertical plane passing through the axis of rotation of the drum 11, are supported in bearings 63 attached to suitable framework 64.

When it is desired to heat-treat a material by the apparatus shown, the burner is set into operation and products of combustion or hot gases are passed through the drum in a direction indicated by the arrows 70, these hot gases passing upward through the flue, as shown. When the apparatus has become heated, the material to be treated is fed into the inlet end of the drum 11 by means of the chute 15, this material passing therethrough in a direction indicated by the arrows 71. It will be noted that the hot gases run counter-current to the material to be treated. The drum 11 is rotated at this time and the material passing therethrough is thoroughly agitated and brought into intimate contact with the hot gases that pass through the drum. The agitating member 17 terminates to the left of the right end of the annular outlet 21. Consequently, the material which is being treated tends to lie on the bottom of the drum at this point, and by reason of the fact that the drum is slightly inclined, as shown, will travel to the left and through the annular outlet 21. When the material passes into this annular outlet 21, it is brought into an area of very high temperature and any remaining moisture will be removed therefrom. It will be seen that by extending the fire-box into the end of the drum 11 and by providing the outlet around the fire-box, the heat of radiation is utilized to maintain the annular outlet 21 at a very high temperature.

As the material passes from the end of the drum 11, it falls into the space within the screening means 27. Since the screening means rotates with the drum, the material is agitated, and since the lowermost part of the screening means declines or slants downward to the right, the material is fed in a rightward direction. Any material which is small enough to pass through

the left screen 28 will fall into the screen 29. Any material which is small enough to pass through the screen 29 will fall into the bin 43, and any material which falls onto the screen 29 but is too large to pass therethrough, will travel along the screen 29 and fall from the end thereof into the bin 44, as indicated. The material which is too large to pass through the left screen 28 passes to the right and over the right screen 28. The right screen is coarser than the left screen 28 and part of the material will pass therethrough and into the bin 45. The large material which does not pass through either of the screens 28 passes from the end of the right screen 28 into the bin 46.

10 The first important feature of my invention is the extending of the heater tube or fire-box 20 into the end of the drum 11 and forming the outlet between the fire-box and the wall of the drum. It is of course preferable to have the parts concentric and to have the annular outlet 21 completely annular in order that the material may pass from the drum at all rotational positions of the drum. If the material does not 20 need to be screened, the screening means shown may be eliminated, and if the material does not have to be kept heated, the housing and bins may be eliminated and a suitable receptacle provided at the outlet end of the drum. As mentioned in the introductory part of the specification, I prefer to have the fire-box 20 secured to the drum 11 and rotatable therewith in order that the outer end of the fire-box may cooperate with the support means, and in order that the 30 support means may be on the exterior of the apparatus. This is not essential, however, and if desired the fire-box may be made stationary and the support means may be associated with the left end of the drum 11 by providing a bearing ring thereon, and by providing suitable supporting rollers such as the rollers 62. If this arrangement were provided, the drum would rotate around the inner end of the fire-box 20. The burner 52 and the flame shield 54a are 40 typical of any type of hot gas supply means which are suitable to supply hot gases to the fire-box 20. Various other means could be provided without departing from the invention.

When it is desired to screen the material, the 50 screening means of my invention may be utilized. The screening means is placed around the left end of the drum 11 in order to economize on space. If the screening means were placed adjacent to the drum and not around it, the apparatus would be somewhat longer and it would be difficult to arrange the fire-tube, as shown. The screening means is supported partly by the drum and partly by the fire-tube. The fire-tube has secured thereto the end plate 30 which supports the left end of the screening means and acts as a closure which directs the material in a rightward direction along the screens 28 and 29. The bins 43 to 46 inclusive are included in the housing 38 in order that they may be kept heated.

For convenience, I have illustrated different parts of the invention as being of conventional construction. For example, the drum 11 is provided with conventional agitating members and 70 helical blades and is provided in cylindrical form and on a slight incline. If it is desirable to provide a stationary drum 11 with feeding means therein, such a structure comes within the scope of my invention, provided it utilizes the 75 feature of the tube or fire-box 20 extending into

the end of the drum 11 and providing an outlet passage between the fire-box and the wall of the drum. Other parts of the apparatus have also been made of conventional construction and, as explained above, I do not want to be limited to such details, but I do want my invention to be construed according to the scope of the appended claims.

I claim as my invention:

1. In a drier of the class described, the combination of: a drum through which the material to be treated is passed; a fire-box extending into one end of said drum and partially supported exteriorly thereof, said fire-box providing an annular outlet in the end of said drum around said fire-box; and a screening means around the end of said drum and so inclined that said material tends to travel therethrough by gravity, said screening means being attached to and rotatable with said fire-box.

2. In a drier of the class described, the combination of: a drum through which the material to be treated is passed in one direction; a fire-box extending into one end of said drum and partially supported exteriorly thereof, said fire-box providing an annular outlet in the end of said drum around said fire-box; and a screening means around the end of said drum and so inclined that said material tends to travel therethrough by gravity in a direction opposite to the travel of said material through said drum, said screening means being attached to and rotatable with said fire-box.

3. In a drier of the class described, the combination of: an imperforate rotatable drum through which material to be treated is passed; a fire box extending into said drum and providing an annular outlet at one end thereof; screening means of larger diameter than said drum and surrounding said drum at said outlet end of said drum; and support means whereby said screening means is supported by said fire box.

4. In a drier of the class described, the combination of: a rotatable drum through which material to be treated is passed; a fire box extending into said drum and providing an annular outlet at one end thereof; screening means of larger diameter than said drum and surrounding said drum at said outlet end thereof, said screening means projecting beyond the end of said drum; and support means extending inwardly from said projecting end of said screening means to said fire box.

5. In a drier of the class described, the combination of: an imperforate rotatable drum through which material to be treated is passed, said drum having an outlet at one end thereof; a member extending into the outlet end of said drum, thus forming an annular outlet passage; screening means surrounding said drum and extending beyond the end of said drum; and means extending inwardly from said screening means to said member whereby said material is directed from said annular outlet into said screening means.

6. In a drier of the class described, the combination of: an imperforate rotatable drum through which material to be treated is passed, said drum having an outlet at one end thereof; screening means surrounding said drum and extending beyond the end of said drum; and means extending inwardly beyond the outlet end of said drum, whereby said material is directed from said outlet into said screening means.
